UNITED STATES PATENT OFFICE.

HELEN B. BARNBROOK, OF PROVIDENCE, RHODE ISLAND.

PAPER-BINDING TOOL.

Application filed April 1, 1926. Serial No. 99,157.

My invention relates to tools for binding loose papers and the like into a compact, neatly bound book.

My invention comprises a plurality of posts having means to contain the ends of binding cord therein adjustably detachably mounted on a base and having posts intermediate said posts provided with means to temporarily engage the intermediate portions of binding cord having the ends thereof threaded downwardly through said other posts. In my preferred embodiment my invention comprises two outer hollow posts and preferably a solid center post suitably mounted on such a base. I believe I am the first to provide a device of this description provided with means to adjustably mount certain of said posts on said base, whereby said unit may be adjusted to bind the various sizes of papers, such as say business letter size, legal cap size, normally used in a business office, and newspapers. An object of my invention therefore is to provide a unitary device of this description, adjustable to bind papers of various ranges of width.

As I preferably detachably mount the posts on the base, I provide a unit which may be disassembled and packed for shipping purposes in a compact unit.

These and such other objects of my invention as may hereinafter appear will be best understood from a description of the accompanying drawings which illustrate one embodiment of my invention and the steps necessary to form a completely bound book of office papers.

In the drawings, Fig. 1 is a perspective view of my invention.

Fig. 2 is a longitudinal sectional view thereof taken along the line 2—2 of Fig. 1.

Fig. 3 is a transverse sectional view taken along the line 3—3 of Fig. 1.

Fig. 4 is a diagrammatic perspective view after the sheets of paper desired to be bound have been laid on the posts, suitable covers therefor placed thereon, one of said covers being provided with a suitable gummed flap and with a binding cord having the ends thereof threaded downwardly through said outer hollow posts and having the intermediate portion thereof engaged by the hook on said center post.

Fig. 5 is a diagrammatic perspective view illustrating how when said papers and covers are lifted en bloc from my tool, the

hook draws down the center portion of said binding cord to form a loop and the ends of the binding cord withdraw from said outer hollow posts to form ends adapted to be tied to said loop to bind said papers together.

Fig. 6 is a reverse plan view of one end of my invention.

Fig. 7 is a view of an end of a book with the ends of the binding cord tied to the loop to bind the papers together.

Fig. 8 is a perspective view of the papers compactly bound into a neat book and having the outer flap secured over and on top of the binding cord.

In the drawings, wherein like characters of reference indicate like parts throughout, 10 generally indicates a binding tool constructed in accordance with the principles of my invention. 12 indicates a suitable base therefor which is preferably narrow and is slightly longer than the width of the widest paper to be bound. 14^a and 14^b illustrate the outer hollow posts and 16 illustrates the center post of my invention, all of which are

adapted to be secured to said base, preferably in the detachable manner to be explained. In order that the hollow posts 14^a and 14^b may be adjustably secured to said

base in a convenient manner, I provide the deep groove 15 extending centrally, longitudinally on the bottom of said base and the longitudinal slots 18^a and 18^b extending centrally from said groove 15 from substantially the ends thereof to the top of said base, thus forming flanges 28 having the lower sides spaced a substantial amount from the bottom of said base. The groove 15 may be formed in the bottom of said base 12 in any suitable manner, such as by casting, stamping, or otherwise. The center post 16 is preferably detachably secured to the

solid center portion 22 of said base by having the thread 30 on the lower end thereof adapted to register in the threaded hole 32 in said center portion 22. Said center post 16 is provided with means on the upper end thereof to temporarily engage the intermediate portion of a binding cord, in my preferred embodiment said means preferably comprising the hook 34. While said outer posts 14^a and 14^b may be constructed in any suitable manner to hold the ends of the binding cord therein, such as by providing longitudinal slits therein, etc., they are prefer-

ably constructed hollow as shown and have the washers 36^a and 36^b permanently secured thereto near the lower ends 38 thereof and the outer peripheries 40 of the lower ends 5 thereof preferably threaded as shown below said washers 36^a and 36^b. To detachably secure the lower ends 38 of said hollow posts 14^a and 14^b to said base 12, I preferably provide the comparatively thin nuts 42^a and 42^b 10 provided with the central threaded holes 44 adapted to engage the threaded lower ends of said hollow posts 14^a and 14^b to adjustably clamp them to the flanges 28. In order that said posts 14^a and 14^b may be readily 15 adjusted longitudinally of said slots 18^a and 18^b without removing the base 12 from its support, the nuts 42^a and 42^b preferably have their peripheries flattened at diametrically opposite sides thereof as at 46 to abut 20 the sides of the upper portion 48 of said groove 15 immediately below said flanges 28. It is thus obvious that in turning the hollow posts 14^a and 14^b by hand counter-clockwise, that as the sides 46 of said nuts 25 42^a and 42^b are kept from turning in said groove 15 that said posts 14^a and 14^b will become unloosened from said nuts 42^a and 42^b, so that said posts 14^a and 14^b may be moved to a new position on said slots 18^a 30 and 18^b, and on then turning said posts clockwise the nuts 42^a and 42^b still prevented from turning by the sides 46, will similarly secure said posts to said base in a new position by clamping said flanges 28 against said 35 washers 36^a and 36^b. As stated, the hollow posts 14^a and 14^b are adapted to contain the ends 50^a and 50^b of a binding cord 52 therein. The nuts 42^a and 42^b are preferably thin, so that the ends 50^a and 50^b of said 40 cord may fold as shown in Fig. 2 within the lower portion of said groove 15 below said nuts.

When it is desired to use my improved tool to bind sheets of paper, said sheets of paper 54 are marginally perforated along their width as at 56 at spaced intervals corresponding to the spacings of said posts, the posts 14^a and 14^b having been adjusted, as hitherto explained in any suitable manner, 45 and the perforations 56 in said papers made either with a suitable punch or by insertion of said papers over said posts, the ends of which may be sharpened if desired. The marginal perforations 56 are thus formed on 50 said papers and said papers 54 are laid on said posts. If it is desired to form a complete book, the book covers 58 and 60 may be inserted thereon, above and below said papers respectively. To completely cover 55 all the bound end of the book, a marginal flap 62 is preferably provided, having one edge 64 thereof gummed and attached to one edge 66 of one of said covers. In my preferred embodiment both said covers 58 and 60 and the edge 66 of the attached flap are

correspondingly marginally perforated as at 68 to correspond with the marginal perforations 56 in said papers.

A suitable binding cord, tape or other material 52 is then taken and the ends 50^a and 50^b thereof suitably dropped down through said hollow posts 14^a and 14^b and the center portion 53 of said cord 52 engaged by the hook 34 of said center post 16. It is obvious that as the flanges 28 are spaced a substantial amount from the bottom of the base 12, a considerable space will be left in said groove 15 beneath the thin nuts 44 and the lower ends of said posts 14^a and 14^b, so as to permit the ends 50^a and 50^b to freely 80 drop through said hollow posts 14^a and 14^b and not get caught within said hollow bores.

When said papers 54 and covers 58 and 60 are raised en bloc from said posts as shown in Fig. 5, it is obvious that the hook 85 34 of said center post 16 will draw the center portion 53 of said binding cord 52 downwards through the intermediate perforations in said covers and papers to form the downwardly projecting loop 55 and the ends 90 50^a and 50^b of said cord will be pulled upwards until they are withdrawn from within in said hollow posts 14^a and 14^b to form the ends 50^a and 50^b, adapted to be tied to said loop 55 to bind said papers 54 and covers 95 58 and 60 together. The ends 50^a and 50^b are then tied to said loop 55 as illustrated in Fig. 7. The free gummed end 70 of said flap 62 is then inserted over the tied marginal edge of said papers and covers respectively and the gummed edge 70 is permanently gummed to the lower cover 60 to completely hide all the binding material and to cover the exposed portions of the binding 100 cord 52 to form the completely bound book 105 72 of papers as illustrated in Fig. 8.

While it is desirable to employ the covers 58 and 60 for said papers and also the gummed flap 62, it is obvious that they may be dispensed with if desired. It is also obvious that in place of one intermediate post 16, a plurality of intermediate posts and hollow posts may be employed and two ends threaded downward through each hollow post in case it is desired to obtain a more secure binding for comparatively large papers and I have employed the singular throughout the claims to include the plural where this is employed.

It is obvious that I have provided a tool which may be knocked down and conveniently packed in small compass, which is adjustable so as to bind the normal sized papers of every office, simple, inexpensive and which permits the most inexperienced office employee to become his own book binder.

It is understood that my invention is not limited to the specific embodiment shown and that various deviations may be made

therefrom without departing from the spirit and scope of the appended claims.

What I claim as new and desire to secure by Letters Patent is:

- 5 1. A tool for use in binding papers and the like comprising a base having a deep groove extending longitudinally and centrally and upwardly from the bottom thereof and having slots located centrally thereof, the slots extending from said groove to the top of the base and from near the ends of the base to nearly the center thereof, whereby longitudinally extending flanges are formed spaced a substantial amount from the plane of the bottom of the base and whereby a solid portion is left at the center of the base, a central post, having a hook at its upper end, threadably engaged with the solid center portion of the base, a hollow post on each side of the center post having a washer secured thereto near its lower end and being externally threaded at its lower end, clamping nuts, internally threaded, for engaging the lower ends of the respective hollow posts for variably positioning the posts in their respective slots, the nuts and the lower ends of the posts being spaced from the plane of the bottom of the base, the nuts being flattened for engaging with the sides of the grooves, below the flanges.
- 10 15 20 25

2. A tool for use in binding papers and the like comprising a base having a deep groove extending longitudinally and centrally and upwardly from the bottom thereof and having slots located centrally thereof, the slots extending from said groove to
- 30

the top of the base and from near the ends of the base to nearly the center thereof, whereby longitudinally extending flanges are formed spaced a substantial amount from the plane of the bottom of the base and whereby a solid portion is left at the center of the base, a central post, having a hook at its upper end, threadably engaged with the solid center portion of the base, a hollow post on each side of the center post having a washer secured thereto near its lower end and being externally threaded at its lower end, clamping nuts, internally threaded, for engaging the lower ends of the respective hollow posts for variably positioning the posts in their respective slots, the nuts and the lower ends of the posts being spaced from the plane of the bottom of the base, the nuts being flattened for engaging with the sides of the grooves, below the flanges.

3. A tool for use in binding papers and the like, comprising a base, a central post detachably engageable with the center portion of said base and having a hook on the upper end thereof, a hollow post on each side of said center portion and means to detachably clamp said hollow posts to said base at points spaced variable distances from said center post.

In testimony whereof I affix my signature.

HELEN B. BARNBROOK.
